UNITED STATES PATENT OFFICE

GODFREY STIBBE, OF LEICESTER, ENGLAND, ASSIGNOR TO HEMPHILL COMPANY, OF CENTRAL FALLS, RHODE ISLAND, A CORPORATION OF MASSACHUSETTS

PATTERNING MECHANISM FOR CIRCULAR KNITTING MACHINES

Application filed August 9, 1927, Serial No. 211,703, and in Great Britain August 12, 1928.

This invention has reference to knitting machines of the type equipped with independent needles and elements such as sinkers or like instrumentalities movable relatively thereto for acting on yarns fed in plating relation to change the plating effect, and relates more particularly to pattern mechanism employed in such machines for selecting said elements to bring about the required pattern changes.

Heretofore for this purpose this mechanism has included a pattern wheel or like rotary device equipped with bits or jacks fixed in or on the perimeter and prearranged according to the pattern desired, consequently the extent of the pattern produced by any one wheel has been determined by the circumference of the wheel.

The object of this invention is to enable the extent of the pattern to be increased beyond that normally provided for by the pattern wheel, and is achieved by providing a pattern device the operative portion of which varies or is variable while the machine is working.

Specific examples of the invention are illustrated in the accompanying drawings to which reference will be made in the following further description.

In the drawings—

Figure 1 is a sectional side elevation of an arrangement employing a pattern wheel with movable jacks and an associated controlling wheel.

Figure 2 is a plan, and

Figure 3 is a front elevation of the same.

Figures 4 and 5 are sectional details illustrating modifications concerned with the controlling wheel.

Figure 6 is a side elevation and

Figure 7 is a plan of an arrangement employing a jacquard band for acting selectively on the aforesaid elements, and

Figure 8 is a detail of means for tensioning the band.

According to one embodiment of the invention there is provided a pattern wheel equipped with jacks, which, for the purpose of selecting the elements, are themselves capable of selection automatically by associated means.

This selection of the jacks in the pattern wheel is brought about automatically and has the effect of varying the arrangement of the said jacks while the wheel is in operation thereby increasing the scope of its selective action on the elements and correspondingly extending the distribution of the pattern in the fabric being knitted.

I may select the movable jacks by means of a controlling wheel of larger diameter than the pattern wheel said controlling wheel being constructed to act upon the jacks for the purpose desired, the extent of the pattern being limited by the circumference of the controlling wheel. For example, I may use a tricked controlling wheel having in the tricks displaceable bits adapted to be set by hand.

In another arrangement for the purpose of further increasing the scope of the mechanism for patterning, I provide the controlling wheel with movable bits for acting selectively upon the jacks in the pattern wheel, the said bits being themselves selected for such action by prearranged pattern means of suitable form, e. g. one or more wheels or equivalent, or jacquard means.

In a modified form of the invention the pattern device may consist of a wheel or disc having combined with it a jacquard band notched, provided with bits or the like or otherwise formed for selective action on the aforesaid elements according to the required pattern. Obviously the operative portion of the device is constituted by that part of the band which passes round the wheel or disc and this varies according to the formation of the band.

The illustrative embodiments of the invention are mainly intended for application to the well known "Banner" circular knitting machine equipped with yarn engaging elements slideable transversely to the needles for the purpose in question and as an example of such Banner machine I refer to the United States patent to Robert H. Lawson, No. 1,605,895, dated November 2, 1926. The invention, however, is not to be regarded as limited to such application.

Referring first to that arrangement illus-

trated in Figures 1 to 3 of the drawings, the pattern wheel 1 is rotatably mounted adjacent to and in horizontal alignment with the dial or bed 2 of the machine in which the plating controlling elements 3 operate. This wheel is provided with radially slidable jacks 4 which, by means of butts 4a and 4b thereon engaging an arcual cam 5 on a cam cap 6 fixed above the wheel are held in an operative (projected) or inoperative (withdrawn) position as they pass the elements 3. At one point in the wheel these jacks are all projected and are later selectively acted upon by bits 7 in a rotary controlling wheel 8 such bits being also adapted for projection and retraction in a selected manner as the wheel rotates as will be subsequently explained.

Where a bit 7 is projected it engages a corresponding jack 4, as represented in Figures 1 and 2, and pushes the same inwards so that its butt 4a is located behind the cam 5 whereby it is held inoperative until it has passed the dial 2. Where a bit is retracted the corresponding jack in the pattern wheel is not acted on so that it remains projected with its butts on opposite sides of the cam 5 whereby it is held in the operative position as aforesaid. In this position it acts on the opposing element 3 as represented in Figure 1, as it passes the dial 2 and pushes it inwards to bring about reverse plating. The reverse plating preferably is effected by the action of the special instrumentalities or casting off mechanism herein referred to as "elements 3", substantially as disclosed in the patent to Robert H. Lawson, No. 1,605,895, dated November 2, 1926, and the reissue thereof No. 16584, dated April 5, 1927, or as disclosed in the patent to Robert H. Lawson, No. 1,605,896, dated November 2, 1926. A cam 9 is provided on the cap 6 in a gap 5a between the ends of the cam 5 whereby, after the jacks have passed the sinkers all those occupying the inoperative position are projected in readiness for further selection. The cam 10 acts on the butts 4b of the jacks. It will be understood that the gap 5a is located opposite to the point at which the controlling wheel operates and that the jacks move in and out through the gap. Further the jacks operate in radial or substantially radial tricks 1a in the face of the pattern wheel.

It will be observed that the controlling wheel is disposed at right angles to the pattern wheel and that the operative extremities of the bits 7 are formed at right angles to the body portion. In order to ensure effectual contact between the bits and the jacks, the latter have bent outer extremities as shown in Figure 2.

The bits 7 are also slidable in tricks 8a at the periphery of the control wheel and corresponding peripheral notches 8b are provided in the wheel to accommodate the outer extremities of the bits in the inoperative

position. The bits are held in the operative (projected) and inoperative (withdrawn) positions by an arcual cam 10 on a fixed cap 11 being provided with butts 7a and 7b to engage the cam. When a bit is in the operative position the butts thereof are located on opposite sides of the cam, while when the bit is inoperative the butt 7a is located behind the cam. At one point in the wheel all the bits occupy the inoperative position into which they are moved prior to said bits being selected for action on the jacks 4 by a cam 12 which extends into a gap 10a between the ends of the cam 10. In this example the selection of the bits is effected by a rotary selecting disc 13 provided with projections 14 prearranged according to requirements.

This selecting disc is so disposed adjacent to the controlling wheel on the inside of the cam 10 opposite the gap 10a that as it rotates its projections 14 engage the inner ends of corresponding bits 7, as represented in Figure 3, and push the latter outwards to the operative position. Where there are no projections the bits, of course, remain inoperative. Said disc may be interchangeable with others of different diameters and having the projections disposed differently thereon. It is also within the scope of the invention to employ other constructions of discs with bits. The cam 10 has an inclined end 10b to ensure the direction of the bits to their operative or inoperative positions as determined by the disc. Similarly the cam 5 has a bevelled or tapered end 5b in order to ensure the direction of the jacks 4 to their operative or inoperative positions, as determined by the controlling wheel. A guard cam 15 may be provided at the periphery of the cap 11 to prevent excessive projection of the bits 7 at the gap 10a.

The pattern wheel 1 is mounted upon a spindle 16 rotatable in the direction of the arrow (Figure 2) in a bearing 17, and driven through the medium or gears 18 and 19 from the needle cylinder 20. The controlling wheel rotates on a spindle 21 fixed in a bracket 21a connected to the bearing 17 and is driven from the spindle 16 in the direction of the arrow in Figure 3, through bevel gears 22, 23. The gear 22 is attached to the gear 19 and the gear 23 is attached to the controlling wheel. The disc 13 is driven from and in the same direction (see the dotted arrow in Figure 3) as the controlling wheel through gears 24, 25 and 26. Said disc has the gear 26 attached thereto and rotates on a pin 27 fixed in a slot 28 in the cam cap 11 which is fixed on the spindle 21. The intermediate gear 25 rotates on a pin 29 fixed in a slot 30 in said cam cap, and the gear 24 is attached to the control wheel. The slots permit of the adjustment of the selecting disc 130

and intermediate gear when discs of different diameters are employed.

Figure 4 illustrates a modified form of controlling wheel in conjunction with a jacquard band for selecting the bits therein. In this example the controlling wheel 8 is formed with peripheral notches. In each notch 31 a bit 32 is pivotally mounted, each bit being carried by a pin 33 which rests in a circumferential groove 34, all of the bits being held in position by cap sections 35 applied to opposite sides of the controlling wheel. A spring 36 is provided for each bit whereby it is normally held inoperative such springs being interposed between the bits and a ring 37 suitably applied. The controlling wheel has attached to it a pin wheel 38 or equivalent which carries and drives a jacquard band 39 formed with projections 40 or other means for action on the bits, during the rotation of the controlling wheel and push them outwards laterally for action on the corresponding jacks 4. The pin wheel 38 directs the jacquard band 39 preferably through the engagement of the pins upon the wheel with formations upon the band properly spaced with respect to said pins.

In a further modification shown in Figure 5, a controlling wheel 8 has two concentric series of bits 41 and 42 located in the same peripheral notches in the controlling wheel. The outer ends of the inner bits are constructed to overlap and engage the opposing ends of the outer bits, the inner bits being adapted to act selectively on the jacks 4, and controlled by the outer bits upon which the jacquard band 39 operates selectively. For this purpose each outer bit is pivoted centrally in its notch or recess 31 by means of a pin 43 located in a circular groove at 44 in the face of the wheel, and the corresponding inner bit is similarly pivoted in the same notch or recess by a pin 45 located in another groove at 46 concentric with the groove 44. A spring 47 is provided for each inner bit to normally hold it in its inoperative position said springs being located in a cover plate 48 whereby all the bits are held in position. This cover plate is grooved to suit the pivot pins 43 and 45. The springs act through the bits 42 to press the bits 41 outwards into the path of the jacquard band.

As in the previous arrangement the jacquard band is formed with projections 40 or other means for action on the bits 41 and is carried and driven by a pin wheel 38 or equivalent attached to the controlling wheel. Thus when the controlling wheel is driven the jacquard band by means of the projections thereon presses selected bits 41 into the wheel and these bits act on the corresponding inner bits to project them so that in their turn they act on the jacks in the pattern wheel.

It will be understood that in each of the modifications just described, the controlling

wheel is driven and controls the action of the jacks 4 in the manner already explained.

In the embodiment of the invention illustrated in Figures 6 and 7, there is provided a rotatable pin wheel 49 combined with which is a jacquard band 50 provided with projections 51, that portion of the band which passes round the wheel constituting the operative portion of the wheel for selective action of the elements 3. As the wheel or disc rotates the band is driven thereby and said operative portion varies according to the disposition of the projections on the band. The wheel 49 is mounted adjacent to the dial 2 on a spindle 16 and driven, in the direction of the arrow, by gears 18, 19, from the needle cylinder 20.

The surplus portion of the band may extend horizontally round one or more guide pulleys (not shown) of construction common in the art and adjustably arranged at a point remote from the pin wheel or equivalent according to the length of the band. Alternatively, and as illustrated, the band, if of considerable length, can be carried round guide pulleys 52 disposed vertically adjacent to the wheel 49 and at right angles thereto, and round lower pulleys 53 also disposed vertically and at right angles to the upper pulleys, the band being suitably twisted, as shown, to allow it to pass on and off the pin wheel and round the various pulleys. The lower pulleys may be carried by a yoke 54 adjustable up and down on fixed rods 55 by a thumb screw 56 so that the band may be suitably tensioned. If desired, another guide pulley 57 may be disposed horizontally adjacent to the pin wheel to ensure that the band passes on to this wheel in a flat condition.

It will be observed that in the arrangements shown in Figures 4 and 5, the jacquard bands operate edgewise on the bits in the controlling wheels, the projections being disposed accordingly. Suitable guiding and tensioning means (not shown) are provided for these bands. In the arrangement shown in Figures 6 and 7 the face of the jacquard band is presented to the sinkers and the projections 51 are conveniently cut and bent up from one edge of the band. In each case the jacquard band is driven by the pins in the pin wheels registering with holes in the band. Any other suitable construction and arrangement may, however, be adopted.

As regards the jacks 4, preferably each has a bent end for engaging and thereupon moving radially inward the corresponding element 3, there being as many jacks as elements.

The invention is not limited to the precise details of construction and arrangement herein described as these may be varied without departing from the scope of the invention.

What I claim then is:—

1. In a knitting machine organization hav-

ing a series of independent knitting needles and having means to supply yarns thereto and having sinkers or like instrumentalities for engagement with the yarns for control thereof in the production of normal and reverse plating, pattern mechanism for controlling or selecting the sinkers or like instrumentalities, said pattern mechanism comprising a pattern wheel, movable jacks therein for engaging said sinkers or like instrumentalities, a controlling travelling member, displaceable jack engaging bits therein, and movable means having pre-arranged formations for selecting the bits, thereby automatically to vary the operative arrangement of the 10 jacks while the pattern wheel is working.

2. In a knitting machine organization having a series of independent knitting needles and having means to supply yarns thereto and having sinkers or like instrumentalities for engagement with the yarns for control thereof in the production of normal and reverse plating, pattern mechanism for selecting or controlling the sinkers or like instrumentalities comprising a pattern wheel, movable jacks for engaging said sinkers or like instrumentalities, means for rendering the jacks operative for purposes of selection, a controlling wheel, displaceable jack engaging bits carried thereby, means for rendering the bits inactive for purposes of selection, and pre-arranged pattern means for selecting the bits, thereby automatically to render desired jacks inoperative while the pattern wheel is 35 working.

3. In a knitting machine organization having a series of independent knitting needles and having means to supply yarns thereto and having sinkers or like instrumentalities for engagement with the yarns for control thereof in the production of normal and reverse plating, pattern mechanism for engaging or controlling the sinkers or like instrumentalities, jacks radially slidable with respect to said pattern mechanism for engaging said sinkers or like instrumentalities, means for projecting the jacks for purposes of selection, another driven member, jack engaging bits radially slidable, means for 45 retracting said bits for purposes of selection, pre-arranged pattern means for selecting the bits so as automatically to render desired jacks inoperative while the pattern wheel is working, and means whereby the jacks and bits are held operative or inoperative as determined by the bit selecting means.

4. In a knitting machine organization having a series of independent knitting needles and having means to supply yarns thereto and having sinkers or like instrumentalities for engaging with the yarns for control thereof in the production of normal and reverse plating, pattern means for selecting or controlling the sinkers or like instrumentalities, movable jacks carried by said pattern mech-

anism for engaging said sinkers or like instrumentalities, a controlling movable member having displaceable jack engaging bits, and a member constructed and arranged to select bits, thereby automatically to vary the 70 operative engagement of the jacks while the pattern mechanism is working.

In testimony whereof I have signed my name to this specification.
